APPARATUS FOR TRANSFERRING ARTICLES
FROM THE OUTSIDE TO THE INSIDE OF
AN ENCLOSUREHerman W. Clausen, Los Angeles, Calif., assignor
of one-half to Peter C. Clausen, Los Angeles,
Calif.

Application February 17, 1934, Serial No. 711,807

3 Claims. (Cl. 198—209)

This invention relates to an apparatus for transferring articles from the outside to the inside of an enclosure in which an even temperature is to be maintained, and it is an improvement on my United States Letters Patent for an Apparatus for receiving and dispensing blocks of ice, issued February 27, 1934, No. 1,949,040.

The principal object of this invention is to provide an apparatus through which articles can be passed from the exterior to the interior of the enclosure without materially changing the temperature therein, and to that end I provide a housing and door with means connected thereto for forming an oil seal between the walls of the housing and door, so that air cannot easily pass between them. Also the oil in addition to forming an air seal between the before mentioned parts, aids in an easy manipulation of the door to transfer articles as described.

Another object of the invention is to provide an inlet door through which articles such as blocks of ice can be passed with great rapidity. To that end I provide a door having oppositely arranged compartments that are separated by a center wall through which a push rod is extended. This rod is arranged so that it can automatically discharge a block of ice from one compartment onto a conveyor simultaneously with the insertion of another block of ice into the other compartment. That is, when the door is in position to receive an article in one of the compartments and there is a like article in the other, the push rod will be in position to be actuated by the inserted article so that it automatically discharges the other article. By this means, in addition to the easy manner in which the door can be revolved the articles can be passed with great rapidity from the exterior to the interior of the enclosure without materially changing the temperature therein.

Other objects, advantages and features of invention may appear from the accompanying drawing, the subjoined detailed description and the appended claims.

The accompanying drawing illustrates the invention, in which:

Fig. 1 is a fragmental central section through the apparatus on the line 1—1 of Fig. 2, showing it arranged to transfer articles from the outside of the enclosure to the inside thereof, with means for discharging them onto a conveyor that is fragmentally shown.

Fig. 2 is a fragmental cross section on line 2—2, Fig. 1, showing the means for forming an air seal between the walls of the door and housing, and also showing the push rod in position to be actuated by the insertion of one block of ice so it will discharge a block of ice from the opposite compartment onto the conveyor.

Fig. 3 is a plan view of the four-piece housing

detached from the wall, and the door therein that is indicated by dotted lines.

Fig. 4 is a section on line 4—4 of Fig. 3.

In detail my apparatus includes a split housing 10 that is preferably secured in the rear wall 11 of an enclosure 12, as semidiagrammatically shown in Figs. 1 and 2.

In this instance the enclosure 12 is for receiving and dispensing blocks of ice 13, it being understood that it can be used for other purposes. When used for receiving and dispensing blocks of ice and the like, the walls of the enclosure are lined with insulating material 14, and the housing 10 is secured therein to prevent air from passing therethrough so that an even temperature can be maintained therein.

Also the door 15 is rotatably mounted in the housing 10 so that air can not pass between the walls of the door and housing as an oil seal is interposed between them.

The housing is preferably formed of four parts that are secured together by means of registering lugs 17 and bolts 16 and it is secured in the wall 11 by means of flanges 18 and screws 19, as best shown in Fig. 1. This housing also includes the upper and lower seats 20 for the ball bearings 21 in which the spindles 22 of the rotary door 15 are mounted.

The upper seat 20 is provided with a cap 23 that is connected with an oil receptacle 24 by a pipe 25 so that oil can pass through the upper ball bearing 21 into the oil channels 26 that are arranged to carry the oil in between and grease the outer walls of the door 15 and the inner wall of the housing 10 to thereby form an oil seal between them in addition to which the oil lubricates the ball bearings so that the door can be easily rotated.

Preferably the oil receptacle 24 is inclined upwardly and has its inlet end extended through the wall 11 and provided with an inlet valve 27 so it can be filled and replenished with oil from the exterior of the wall.

Channels 26 are formed in the upper disk shaped wall of the door 15, and they extend radially from the upper ball bearing 21 outward to the inner wall of the housing 10, where they are normally in register with vertical channels 126.

The channels 126 are arranged in the inner wall of the housing 10, and the outer wall of the door 15 so they are in register when the door is in its charging and discharging position.

The lower ends of the channels 126 are normally in register with the outer ends of the lower radially extending channels 226 that are formed in the lower disk-shaped wall of the door 15. The inner ends of the channels 226 discharge into the lower ball bearing 21. The channels 26, 126 and 226 are arranged so that normally heavy oil can pass from the container 24 down

through the upper ball bearing 21, radially out over the door 15 and down between its outer vertical walls and the inner vertical wall of the housing; after which it passes through the channels 226 into the lower ball bearing 21.

It is obvious that when the door is rotated the heavy oil will be spread over the outer wall of the door 15, and the inner wall of the housing 10 to form an air seal between them.

10 The spreading of the heavy oil over the walls, as stated, prevents waste of the oil when the vertical grooves of the door are brought into the open regions of the housing.

15 The door 10 includes the top and bottom disk-shaped walls 28 and 29 that are integral with the semi-circular walls 30, spaced parallel walls 31 and center cross walls 32. The walls 28, 29, 31 and 32 are arranged to form oppositely arranged open end compartments 33 and 34 into which the blocks of ice 13 or other articles can be inserted and moved from the outside to the inside of the enclosure, and normally the open ends of these compartments are held in register with the openings 35 and 36 in the housing 10 by the spring latch 37.

20 The spring latch 37 is secured in a recess 38 in the bottom of the housing 10 so that normally it extends into one or the other of the indents 39, 40, and when so seated the openings 33, 34 of the door are in register with the openings 35 and 36 of the housing. That is, when the latch 37 engages the indent 39 the opening 33 is in register with the opening 35 and opening 34 registers with opening 36; and when the latch engages the indent 40 the registering of the openings is reversed.

25 The spring latch 37 is constructed so that a relatively light arc thrust on the door will cause it to be unseated from one or the other of the indents so the door can be given a half turn to reverse the positions of its open end compartments.

30 A thrust rod 41 is slidably mounted in the center wall 32 and its purpose is to automatically discharge a block of ice from one of said compartments onto a conveyor 42 when a similar block of ice is thrust into the other compartment. This feature of invention is very clearly shown in Figs. 1 and 2 of the drawing.

35 In Fig. 1 it is assumed that the block of ice 13a has just been thrust into the compartment 33 with sufficient force to actuate the rod 41 to discharge the block of ice 13b from the compartment 34 onto the conveyor 42.

40 In Fig. 2 it is assumed that the door of Fig. 1 has been given a half-rotation which reverses the position of the rod 41 so that when the block of ice 13c is thrust into the compartment 34 the rod 41 will be again actuated to discharge the block of ice 13a onto the conveyor.

45 A roller 43 is arranged below the opening 36 in the housing 10 to help carry the blocks of ice over onto the rollers 44 of the conveyor 42; and guides 45 are arranged on opposite sides of the opening 36 for the purpose of guiding the blocks as they are discharged.

50 The conveyor 42 is substantially like that shown in my patent application hereinbefore mentioned. It includes a support 46 for the rollers 44 that also supports sprocket wheels 47, carrier chains 48 and spacing roller 49 and the blocks of ice 13 move down the conveyor by gravity.

From the foregoing it can be readily seen that the door 15 can be easily manipulated to rapidly transfer blocks of ice or like articles from the outside to the inside of the enclosure without materially changing the temperature therein.

5 In operation a block of ice or like article is thrust into the compartment that is in register with the outer opening in the housing 10 and at the same time an arc thrust is imparted through the block of ice to the door that is sufficient to disengage the latch 37 and give the door a half turn.

10 In other words, an operator on placing a block of ice in a compartment of the door also gives it an arc thrust either toward the right or left which, 15 in addition to unlatching the door, will also cause it to turn a half revolution to another latching position, in which movement the block of ice is transferred from the outside to the inside of the enclosure, and an empty compartment in the door 20 is moved to a filling position.

25 In this movement the outer wall of the door and inner wall of the housing are greased to form an air seal between them so that the transfer of blocks of ice from the outside to the inside of the compartment is accomplished with great speed and also without materially changing the temperature in the enclosure.

30 I claim as my invention:

1. An apparatus for transferring articles from the outside to the inside of an enclosure in which an even temperature is to be maintained, including a split housing secured in a wall of said enclosure, upper and lower bearing seats in said housing, bearings therein, a revolving door, spin- 35 dles to said door that are mounted in said bearings, and means for forming an oil seal between the inner walls of said housing and the outer wall of said door, said means including an oil receptacle in communication with radial and vertical 40 grooves in the walls of said housing and door.

2. An apparatus for transferring articles from the outside to the inside of an enclosure in which an even temperature is to be maintained including a housing secured in the wall of said enclosure, a door rotatably mounted in said housing, said door and housing having engaging walls with radial and vertical oil channels arranged therein so that when the door is rotated said channels will spread lubricant over the inner walls of said 50 housing and the outer walls of said door to thereby form an air seal between them, and means for supplying the lubricant to said channels.

3. An apparatus for transferring articles from the outside to the inside of an enclosure in which an even temperature is to be maintained including a housing secured in the wall of said enclosure, a door rotatably mounted in said housing, said door and housing having normally registering lub- 55 bricating channels therein arranged so that lub- 60 bricant will first pass through radial channels in the upper wall of the door to vertical channels in the semicircular walls thereof and through the vertical channels to lower radial channels in the lower wall of the door, also said channels ar- 65 ranged so that when said door is rotated they will spread lubricant over the outer walls of the door and also over the inner walls of the housing, and a receptacle above said housing for supplying lub- 70 bricant to said channels.

HERMAN W. CLAUSEN.
